GREASE INTERCEPTOR

Filed June 22, 1934

UNITED STATES PATENT OFFICE

2,081,215

GREASE INTERCEPTER

Edward W. N. Boosey, Detroit, Mich.

Application June 22, 1934, Serial No. 731,918

6 Claims. (Cl. 210—56)

This invention relates to grease interceptors, the object being to provide a simple and comparatively inexpensive structure with a comparatively high efficiency in causing a separation of oil, grease and the like from water discharged through a waste line and thus prevent discharge of oil and grease into the sewer to which the waste line discharges.

A feature and object of the invention is to provide a construction in which the waste water flowing into the interceptor is caused to flow in a shallow stream along the bottom wall or an inclined wall thereof between an inlet and an outlet to provide a time interval permitting the oil or grease to pass upwardly out of the stream into the body of the water in the interceptor.

It is also an object of the invention to provide a grease interceptor including a hollow body having a means for directing the flow from an inlet toward an outlet along one or more walls of the body in a stream of shallow depth and to provide in conjunction therewith a deflector or deflectors so positioned as to practically determine the depth of the stream and provide a means for holding the waste fluid in the body of the trap from material agitation or movement and thus permit the oils, greases etc., to rise to the surface of the fluid in the body of the interceptor.

Another feature and object of the invention is to provide within a body of an interceptor a plate having louvres formed therein to provide deflectors, which plate is so positioned as to cause the flow from the inlet to pass in a stream of little depth and to permit oils and greases to rise and pass through the louvres of the body into the waste material of the trap.

It is further an object and feature of the invention to provide a means within the interceptor for deflecting the flow from the inlet toward the bottom wall or walls and to provide a deflector adjacent the outlet so positioned as to permit or cause oils and greases to pass up out of the flowing stream and thus separate the oils and greases from the waste water flowing through the outlet.

It is also an object and feature of this invention to provide in conjunction with the foregoing features of the invention a means for cooling the waste fluid either at the inlet or at some other portion of the body as, for instance, adjacent the outlet in the path of movement of the waste fluid to tend to cool the waste fluid to thereby more readily cause a separation of the greases from the fluid passing through the outlet.

These and other objects and novel features of the invention are hereinafter more fully described

and claimed, and the preferred forms of construction of a grease interceptor embodying my invention are shown in the accompanying drawing in which—

Fig. 1 is a vertical section of a grease interceptor showing one form of construction. 5

Fig. 2 is a section taken on line 2—2 of Fig. 1.

Fig. 3 is a similar section showing a different form of construction including a removable plate having louvres through which grease and oil may rise to the surface of the liquid body and including a cooling element forming a baffle adjacent the outlet. 10

In the form of the invention shown in Fig. 1, the body of the interceptor is indicated generally 15 at 1, the upper end of which is flanged to receive a cover member 2 which may be of any desired form preferably removably secured in place in a manner to prevent leakage of the gas or liquid. The inlet in this form of the invention is adjacent 20 the top of the interceptor as indicated at 3 and the wall 4 of the interceptor below the said inlet is inclined to the vertical and a substantially horizontal bottom wall 5 is provided which wall, opposite the outlet, has a pocket 6 extending across the 25 same with which the outlet pipe 7 is connected. The outlet or discharge pipe extends upwardly preferably to above the inlet and determines the possible level of the liquid in the body.

In one form of construction I provide a baffle 30 at the inlet, preferably in the form of a hollow body 8, supported at its lower edge in lugs 9 provided on opposite side walls and resting at its upper end against the lugs 10 also provided on opposite side walls of the body. 35

As shown more particularly in Fig. 2, the side wall 11 is apertured to permit the nipples 12 and 13 to be passed therethrough to threaded engagement with the threaded apertures provided in the end wall of the hollow baffle 8. These nipples may be connected with the pipes 15 and 16 through which cold fluid may be passed into the baffle. This cold body within the liquid of the interceptor tends to cool the entire body and thus congeal the greases which more readily tend 40 to rise to the surface. Packing nuts 14 are provided on the nipples to prevent leakage from the interior of the hollow body. It is to be noted that the wall 18 of the hollow baffle 8 is downwardly inclined practically parallel with the angularly disposed wall 4 of the body and thus the stream entering the interceptor does not flow directly into the body of the liquid contained therein but is caused to take a path 45 down the inclined wall and thence to the outlet. 50

55

Between the baffle 8 and the outlet are a series of vertically positioned plates indicated generally at 19, 19, the lower edges of which define the depth of the moving stream from the inlet to the outlet and also tend to prevent eddy currents of any material detriment in the body of the liquid in the interceptor. Thus also the oils and greases may more readily rise from the flowing stream and pass upwardly between the baffles 19 to the surface of the liquid in body.

In this construction providing a pocket 6 at the outlet end, the terminal baffle 19^a of the series of vertically positioned baffles lies between the end of the horizontal wall 5 and the outlet conduit 7 and this baffle adjacent the outlet, due to its causing a change in the direction of the flow of the stream from the inlet, provides a final means to intercept the oils and greases and time period to permit their rise from the flowing stream into the body of the interceptor.

In the structure shown in Fig. 3, the same general principles of operation are involved as described relative to the structure shown in Fig. 1. The structure differs, however, in respect to the form and position of the baffle members. In Fig. 3 a plate 20 is provided having a vertical portion 21 of an imperforate surface opposite the inlet 3^a and an inclined wall 22 in which louvres 23 are provided which are so positioned as to place a vertical wall toward the stream flowing between the inclined portion 22 and the inclined wall of the hollow body 25. The louvred plate is removable and rests against lugs 26 adjacent the upper end and 27 at the lower end on opposite side walls of the body and the lower end of the plate is spaced from the bottom horizontal wall 28 of the body thus providing a shallow stream from which the greases and oils may rise through the louvres and from the horizontal portion upwardly into the body liquid contained in the interceptor.

In this construction there is a pocket 29 formed at the discharge side of the bottom to which the discharge conduit 30 is connected and a hollow baffle 31 is provided at the outlet which functions after the manner of the baffle 19^a shown in Fig. 1, that is, fluid flowing along the bottom wall of the body strikes the inclined wall of the baffle 31 produces a turbulence at this point and time period for greases to rise into the body of liquid above the outlet. The baffle member 31 is in all essential respects similar to the hollow baffle 8 of Fig. 1 containing the cold coils which are to be understood as being connected thereto in the same general manner as described relative to the construction shown in Figs. 1 and 2. The member 31 is spaced from the vertical side wall on the discharge side of the body and, as the discharge member 30 extends upwardly to a point slightly higher than the inlet, a body of liquid is maintained in the hollow body at all times and the construction provides a pathway for a stream of fluid flowing thereinto along the bottom surface of the body as in the construction first described.

In all of the constructions shown, with liquid at normal level in the body, any liquid thereafter flowing into the body will raise the level of the liquid tending to compress the gases that exist and may accumulate below the top above the liquid level and as this liquid is above the outlet, flow will be produced to the outlet.

In both of the structures there is a cover member that is removable and yet seals the hollow body to prevent escape of gas. This sealing of the cover may be accomplished in any convenient

way as by bolts or screws. In either of the structures shown, both the inlet and the outlet are provided with baffle members and are so arranged as to cause the inflowing stream to pass along the bottom in a shallow depth from which greases and oils may readily rise into the body of the liquid.

By the general arrangement of parts described, a device embodying the various objects of my invention is secured and it is believed evident from the foregoing that the structure is comparatively simple and inexpensive, is composed of few parts not requiring any particular machine work or finishing.

Having thus briefly described my invention, its utility and mode of operation, what I claim and desire to secure by Letters Patent of the United States is—

1. A grease interceptor comprising a hollow body having an inlet on one side thereof near the top and an outlet opening thereinto on the opposite side at the bottom, a baffle within the body adjacent the inlet arranged to direct the inflowing fluid downwardly in a comparatively shallow stream along the bottom of the body, a baffle adjacent the outlet spaced from both the bottom and the top and intercepting the said flowing stream to provide a turbulent condition thereof adjacent the outlet, the practical segregation of the said stream in its flow across the bottom of the body providing a time period permitting oils and greases to rise into the body of the liquid whereby the liquid passing from the interceptor is practically freed of its oil and grease content.

2. A grease interceptor comprising a hollow body having an inlet on one side near the top and an outlet opening thereinto on the opposite side at the bottom, said body having an inclined wall from the inlet to the bottom thereof, a baffle member positioned adjacent the inlet of a form directing the inflowing fluid in a shallow stream along the inclined wall, means providing for the continuance of inflowing fluid in a comparatively shallow stream across the bottom wall, and a baffle adjacent the outlet spaced from both the bottom and the top and intercepting the said stream providing a turbulent condition adjacent the outlet, said means being of a character to permit oils and greases to rise into the liquid in the said body.

3. A grease interceptor comprising a hollow body having an inlet on one side thereof near the top and an outlet opening thereinto on the opposite side at the bottom, baffle means within the body arranged to direct inflowing fluid downwardly to flow in a comparatively shallow stream along the bottom of the body to the outlet, said bottom across one side at the outlet extending to below the general bottom of the body to provide a pocket to which the outlet opens, and a baffle positioned in the body below the top thereof and extending into the said pocket to slightly below the general level of the bottom wall and spaced from the wall of the pocket and adjacent side wall of the hollow body.

4. A grease interceptor comprising a hollow body having an inlet on one side thereof near the top and an outlet opening thereinto on the opposite side at the bottom, baffle means within the body arranged to direct inflowing fluid downwardly to flow in a comparatively shallow stream along the bottom of the body to the outlet, said bottom across one side at the outlet extending to below the general bottom of the body to pro-

vide a pocket to which the outlet opens, and a hollow baffle positioned in the body to extend into the said pocket to slightly below the general level of the bottom wall and spaced from the wall of the pocket and adjacent side wall of the hollow body, and means for chilling the wall of the said hollow baffle.

5. A grease interceptor comprising a hollow body having an inlet on one side thereof near the top and an outlet opening thereinto on the opposite side at the bottom, a hollow baffle within the body adjacent the inlet arranged to direct the inflowing fluid downwardly in a comparatively shallow stream along the bottom of the body, a 10 baffle adjacent the outlet spaced from both the bottom and the top and intercepting the said flowing stream to provide a turbulent condition thereof adjacent the outlet, the practical segregation of the said stream in its flow across the bottom of the body providing a time period permitting oils and greases to rise into the body of the liquid whereby the liquid passing from the interceptor is practically freed of its oil and grease content, and means within the hollow body 15 for chilling the walls thereof.

6. A grease interceptor comprising a hollow body having an inlet at one side adjacent the

top and an opening thereinto on the opposite side at the bottom, said outlet member having a vertically disposed portion extending to a height above the bottom for determining the liquid level within the body, a baffle member comprising a plate positioned comparatively closely to one side of the body and having an imperforate portion opposite the inlet, the said plate tending to cause the inflowing fluid to flow downwardly and thence laterally across the bottom to the outlet in a 10 comparatively shallow stream, said plate below said imperforate portion having louvres providing openings through which greases and oils may pass upwardly from the said stream through the said openings, the louvres being so positioned as 15 to provide a wall preventing the stream from flowing directly into the body of liquid, the lower end of the said louvred plate being spaced from the bottom to determine the depth of the stream flowing across the bottom to the outlet, the main- 20 tenance of the stream of a comparatively shallow depth across the bottom exposing considerable area of inflowing fluid from which oils and greases may rise vertically into the body of the liquid before passing to the outlet. 25
